UNITED STATES PATENT OFFICE.

THOMAS MARTIN, OF PINEVILLE, LOUISIANA.

WHIP-SOCKET.

No. 878,974.

Specification of Letters Patent.

Patented Feb. 11, 1908.

Application filed June 18, 1907. Serial No. 379,585.

To all whom it may concern:

Be it known that I, THOMAS MARTIN, a citizen of the United States, residing at Pineville, in the county of Rapides and State of Louisiana, have invented new and useful Improvements in Whip-Sockets, of which the following is a specification.

This invention relates to whip holders or sockets, and it has for its object to provide a 10 whip socket of simple and efficient construction in which the whip shall be locked or secured against removal by unauthorized parties.

Further objects of the invention are to 15 simplify and improve the construction and operation of this class of devices.

With these and other ends in view which will readily appear as the nature of the invention is better understood, the same consists in the improved construction and novel arrangement and combination of parts which will be hereinafter fully described and particularly pointed out in the claims.

In the accompanying drawing has been 25 illustrated a simple and preferred form of the invention; it being, however, understood that no limitation is necessarily made to the precise structural details therein exhibited, but that changes, alterations and modifications 30 within the scope of the invention may be resorted to when desired.

In the drawing, Figure 1 is a vertical sectional view of a whip socket embodying the invention, showing the whip inserted in the 35 socket. Fig. 2 is a similar view showing the whip in position for removal from the socket.

Corresponding parts in both figures are denoted by like characters of reference.

The improved whip socket includes a 40 housing 1 having at the top thereof an aperture 2 surrounded by an elongated flange or collar 3 through which the whip 4 may be inserted into the socket.

Suitably mounted within the housing 1, in 45 alinement with the aperture 2, is a tubular casing 5 containing a follower 6 consisting of a stem having a head 7 provided with a shoulder or flange 8; said follower being forced in an upward or outward direction by means of 50 a spring 9 coiled upon the stems 6 and operating between the head 7 and a shoulder or offset 10 formed interiorly upon the tubular casing 5.

Pivottally supported adjacent to the sides 55 of the tubular casing 5 are two levers 11—12 provided at their upper ends with terminal

hooks 13 which extend toward each other. Pivottally connected with the lower end of one of the levers, 12, is a tumbler 14, the opposite end of which is pivottally connected 60 with one end of a link or lever 15, the opposite end of which is disposed adjacent to the lower extremity of the lever 11 which may be actuated by said link or lever 15. The tumbler 14 has a notch 16 adapted to be engaged 65 and operated by the bit of the key 17 which may be inserted through a keyhole 18 in one side of the housing.

Pivottally supported within the housing intermediate of and adjacent to the levers 70 11—12 are a pair of dogs 19, the upper ends of which are provided with notches 20 adapted for engagement with the hooked upper extremities 13 of the levers 11 and 12 with which said dogs are constantly held in engagement by the action of springs 21; said dogs are provided with lugs or projections 22 adapted for engagement with the flange 8 upon the head 7 of the follower 6, or with a 75 similar flange 23 formed near the lower end 80 of the handle of the whip 4. It should be stated that the flange or shoulder 8 upon the head 7 of the follower 6 is to be of larger diameter than the flange 23 upon the whip handle, so that while the latter may be released from 85 engagement with the dogs 19 to permit the withdrawal of the whip, the follower will be arrested in its outward movement by said dogs.

When the whip is inserted into the socket 90 by pushing the end of the whip handle through the aperture 2 and between the spring actuated dogs 19 the latter will separate to admit the whip handle, which latter will engage the head 7 of the follower 6, 95 pushing the latter downward into the socket or casing 5 against the tension of the spring 9, until the flange 23 upon the whip handle is engaged and retained by the action of the lugs or projections 22 upon the dogs 19. The 100 whip will thus be held in the socket, securely against removal, until, by means of a suitable key, the tumbler 14 is actuated in the direction of the arrow 24 in Fig. 1, thus causing the parts to assume the position illustrated 105 in Fig. 2. By this action, the upper ends of the levers 11—12 are forced towards each other, thus rocking the dogs 19 upon their respective pivots until the lugs or projections 22 are moved out of the path of the flange 23 110 upon the whip handle; the spring actuated follower will now eject the whip, or force it in

an outward direction from the socket; the follower itself being arrested in its outward movement by the flange or shoulder 8 engaging the lugs or projections 22 of the dogs 5 19. After the bit of the key passes out of engagement with the tumbler 14 the springs 21 will restore the parts of the device to the normal position shown in Fig. 1 of the drawings, with the exception of the spring actuated 10 follower which remains in a projected position until again pushed back within the casting by the insertion of a whip into the socket.

From the foregoing description taken in connection with the drawings hereto annexed, the operation and advantages of this 15 invention will be readily understood.

The construction is simple and inexpensive, and a whip socket embodying the construction herein shown will be found thoroughly 20 efficient for the purpose of preventing the unauthorized removal of the whip from the socket.

Having thus fully described the invention, what is claimed as new is:—

25 1. In a device of the class described, a housing having an aperture surrounded by a flange, a pair of levers pivoted within the housing and having terminal hooks, a pair of dogs pivoted intermediate the levers and 30 having terminal notches engaging the hooks of the levers, said dogs being provided with lugs or projections near their lower ends, and springs engaging the dogs to hold them in engagement with the levers, a spring actuated 35 follower disposed intermediate the levers and dogs and having a flange or shoulder adapted for engagement with the lugs or offsets of the dogs, and means for operating the levers to actuate the dogs.

40 2. In a device of the class described, a housing having an aperture surrounded by a

flange, a pair of levers pivoted within the housing and having terminal hooks, a pair of dogs pivoted intermediate the levers and having terminal notches engaging the hooks 45 of the levers, said dogs being provided with lugs or projections near their lower ends, and springs engaging the dogs to hold them in engagement with the levers, a spring actuated follower disposed intermediate the levers and dogs and having a flange or shoulder adapted for engagement with the lugs or offsets 50 of the dogs, a tumbler connected pivotally with one of the levers, and a pivotally supported link or lever connected pivotally 55 at one end with the free end of the tumbler and having its opposite end disposed in the path of the lower extremity of the other lever.

3. In a device of the class described, a 60 housing having an aperture and a flange surrounding the same, a pair of levers pivoted within the housing and having terminal hooks at their upper ends, a pair of spring actuated dogs supported pivotally intermediate the levers and having notches engaging the terminal hooks of the latter, said dogs being provided with lugs or projections, a spring actuated follower having a head provided with a flange or shoulder adapted for 65 engagement with the lugs or offsets of the dogs, means for simultaneously operating the levers to actuate the spring actuated dogs, and a whip having an annular flange of less diameter than the shoulder or flange upon 70 the head of the spring actuated follower.

In witness whereof, I affix my signature in presence of two witnesses.

THOMAS MARTIN.
